UNITED STATES PATENT OFFICE

136,106

DESIGN FOR AN AUTOMOBILE

George Lim Chieng, New York, N. Y.

Application December 29, 1941, Serial No. 104,903

Term of patent 14 years

To all whom it may concern:

Be it known that I, George Lim Chieng, a citizen of the United States, residing at New York city, county of New York, and State of New York, have invented a new, original, and ornamental Design for an Automobile, of which the following is a specification, reference being had to the accompanying drawing, forming a part thereof, wherein:

The other side of the automobile is the same as that shown.

I claim:

The ornamental design for an automobile, as shown and described.

GEORGE LIM CHIENG.
